UNITED STATES PATENT OFFICE.

HENRI VICTOR DEGOUMOIS, OF CHAUX-DE-FONDS, SWITZERLAND.

DESIGN FOR A WATCHCASE.

SPECIFICATION forming part of Design No. 35,851, dated April 8, 1902.

Application filed December 6, 1901. Serial No. 84,967. Term of patent 14 years.

To all whom it may concern:

Be it known that I, HENRI VICTOR DEGOUMOIS, a citizen of the Republic of Switzerland, and a resident of Chaux-de-Fonds, Switzerland, have invented and produced a new and original Design for Watchcases, of which the following is a specification, reference being had to the accompanying drawing, forming part hereof.

10 The drawing shows a plan view of the back of the watch.

As shown in the drawing, the leading feature of my design consists of a cross, with an open book near the lower end thereof, a cluster of Easter lilies around the cross, and an encircling crown or wreath of thorns. The

cross is indicated at A, the book at B, and the lilies at C, and the wreath of thorns at D. Radiating rays are indicated at E, and stars F are scattered around between the other emblems.

Having thus described my invention, what I claim is—

The design for a watchcase herein shown and described.

25 In witness whereof I have hereunto set my hand in presence of two witnesses.

HENRI VICTOR DEGOUMOIS.

Witnesses:

ARMAND TERRELET,
JULES CHAPUY.
